UNITED STATES PATENT OFFICE.

SAMUEL OLSON, OF OAK PARK, ILLINOIS, ASSIGNOR TO SAMUEL OLSON & COMPANY, OF CHICAGO, ILLINOIS, A CORPORATION OF ILLINOIS.

CONTROL DEVICE FOR PNEUMATIC-DISPATCH-TUBE APPARATUS.

Application filed December 5, 1927. Serial No. 237,715.

This invention relates to controlling devices for pneumatic dispatch tube apparatus and more specifically to automatically actuated devices adapted to be used in connection with a system commonly known as the "partial flow" type. By means of these control devices the flow of air through the system is almost instantaneously increased upon the insertion of a carrier in the tube for transmission, and the flow of air is again reduced to a partial flow after the discharge of the carrier from the tube.

The object of this invention is to provide means in a control device adapted to be operated by reason of the insertion of a carrier in the tube, thus opening the valve which permits maximum flow of air, together with other means for retaining the valve in open position for a predetermined period which may be adjusted so that it is just sufficient to permit the carrier to be impelled through the tube to a point of discharge before the valve closes. It consists in certain features and elements of construction in combination, herein shown and described, and as indicated by the claims.

In the drawings:

Figure 1 is a view illustrating somewhat diagrammatically a complete circuit of pneumatic dispatch tube apparatus equipped with the control device embodying the present invention.

Figure 2 is a transverse sectional view of the control device taken substantially at a medial plane.

Figure 3 is a detail face view of the valve member.

In the pneumatic dispatch tube apparatus circuit illustrated in Figure 1, 10 indicates a suction or vacuum drum, connected by a pipe, 11, to a control device embodying the present invention as indicated generally at 12. It will be understood that the drum may be maintained under reduced pressure or partial vacuum by any suitable means, such as a suction pump (not shown). The opposite end of the device, 12, is connected by a pipe, 13, to the line proper, which consists of two transmission tubes, 14 and 15, constituting the out-going and return runs respectively for a pair of stations which they serve. The control device is disposed in the line adjacent one of the stations and is adapted to regulate the carrier-impelling air flow through the tubes. At the station adjacent

the control device, the outgoing tube, 14, is fitted with a bell-shaped mouth, 16, for the insertion of carriers to be transmitted to the other station, while the opposite end of said tube, 14 (at the other station is provided with a spring-closed discharging flap door, 17, through which the carriers may be discharged at said remote station. The flap door is hinged to a coupling, 18, which connects the adjacent ends of said tubes to form a continuous passage from the control station to the remote station and return. This coupling is also provided with a spring closed flap, 19, on the opposite side for closing the end of the tube, 15, and also permitting insertion of carriers for transmission to the control station which carriers are discharged through a spring flap, 20, hinged to a header, 21, which serves as the interconnecting member in the line between the tubes and the pipe, 13. These spring closed flaps provide substantially air-tight closures for the ends of the tubes so as to make a relatively closed continuous circuit from the mouth, 16, to the discharge end of the tube, 15, at the same end, so that the necessary suction may be produced for impelling a carrier through the tubes from either station to the other.

The control device, 12, which regulates the flow of air through the tubes includes a housing, 25, which is provided with a valve, 26, disposed normally in a closed position as shown in the drawing, and adapted to be opened upon the introduction of a carrier in either tube. In systems of this nature, carriers are not being transmitted continuously, at least not for any great period of time; therefore, for purpose of efficiency, it is desirable to have full carrier impelling suction only when a carrier is in the tube, otherwise when the tubes are free, a partial or restricted flow through the line is sufficient. This restricted flow of air through the tubes facilitates immediate transmission of the carriers upon their introduction in the tubes, and is preferably obtained in a manner to permit the valve to be closed during this idle period. The partial flow of air through the tubes may be accomplished by any suitable means, herein shown as the valve proper. This valve, 26, consists of a valve plate, 27, and a "partial flow" regulating plate, 28, positioned against said valve plate and held in fixed relation thereto by a nut, 29, on a valve stem, 35. Each of the plates, 27 and 28, is provided with one

or more apertures, 27^a and 28^a, respectively, herein shown as four, spaced apart at equal angular distances, and adapted to be adjusted in relation to each other to regulate the "partial flow" of air through the system.

The operation of the valve, 26, is controlled by a pneumatic device which consists of a flexible diaphragm, 30, positioned to form two chambers, 31 and 32. The chamber, 31, is 10 provided with apertures, 33, for venting the same at all times to atmospheric pressure, while the chamber, 32, normally communicates with the pressure in the line through a port, 34, when the valve, 26, is closed. This 15 port is controlled by means responsive to the flow of air in the line, as will hereinafter be described. The valve, 26, is mounted on a valve stem, 35, which extends into said chambers and through said diaphragm to which it 20 is rigidly connected for actuation. The end of said stem beyond the valve is slidably supported in a bearing, 36, integral with the housing, 25, for positioning and aligning said valve; the other end of said stem beyond the 25 diaphragm extends through and beyond the outer walls of the chamber, 31, and is provided with a spring, 37, positioned between said wall and an adjustable collar, 38, on the end of said stem. As is apparent from the 30 drawing, this spring tends to normally maintain the valve in closed position.

The port, 34, of the chamber, 32, is controlled by a valve, 40, carried on the end of an arm, 41, of a bell crank pivoted at 42. The 35 other arm, 43, of the bell crank normally extends obliquely upward and has secured to its outer end a baffle plate or vane, 44, positioned in the path of travel of air when the valve, 26, is open. This baffle plate may be 40 of any desirable shape, such as disk, rectangular, etc.; and preferably of a shape that will not unduly interfere with the flow of air through the system. A spring, 45, is connected to the bell crank arm, 41, and to a take-up 45 rod, 46, extending through the wall of the housing and provided on its end with a nut, 47. It will be understood that when the valve, 26, is closed, the "partial flow" through the system will be inadequate to effect movement of the valve, 40, by the baffle, 44, and the 50 tension on the spring, 45, may be adjusted to a desired strength to forestall any appreciable movement of the baffle until the flow of air through the system obtains a predetermined velocity.

The chamber, 32, is never at any time under full atmospheric pressure; although it is in constant communication with the chamber, 31, by a by-pass or leak port consisting of a 55 passageway, 49, connecting the ports, 50 and 51, of the respective chambers, 31, and 32. The passageway, 49, is controlled by a tapered valve, 52, adapted to be adjusted to regulate the rate of air flow therethrough.

60 The operation of the control device is as

follows: The "partial flow" of air through the system causes a partial vacuum in the tubes and in the chamber, 32, due to the port, 34, being open when the valve, 26, is closed. When a carrier is introduced into the tubes 70 at either of the flap doors, 16 or 19, the air flow through the tubes becomes momentarily choked, thus increasing the vacuum in the tubes and in the chamber, 32. The chamber, 31, being at atmospheric pressure, permits 75 the diaphragm, 30, to respond to the vacuum in the chamber, 32, and move inwardly, shifting the valve stem, 35, thus opening the valve, 26, against the reaction of spring, 37. The opening of the valve, 26, permits full suction 80 in the tube for impelling the carrier to its destination for discharge during which time the vacuum in the chamber, 32, is increased. Substantially at the instant of opening of the valve, 26, the resulting increased flow of air 85 therethrough impinges against the baffle, 44, and forces the valve, 40, to seal the port, 34, of the chamber, 32, against the reaction of the spring, 45.

It will now be clear that the chamber, 32, 90 being closed from communication with the tube, retains the diaphragm in valve opening position. The by-pass valve between said chambers affords a steady, though limited flow of air at atmospheric pressure into the 95 chamber, 32, at all times. During the period that the chamber, 32, is cut off from the line (at which time the carrier is transmitted through the tube and discharged) the pressure in said chamber gradually increases to 100 a point at which the differences in pressure of the chambers is overcome by the spring, 37, which retracts the valve, 26, to closed position. After the valve, 26, closes, the system returns to a partial flow, and the reduced 105 flow of air frees the baffle, 44, and permits the valve, 40, to open the port, 34, with the assistance of the spring, 45; then the device is in condition to again repeat the cycle. It 110 will be understood that the by-pass valve may be so adjusted as to time closing of the valve, 26, immediately upon the discharge of the carrier from the tube.

I claim:

1. In a pneumatic dispatch tube system 115 including a transmission tube for a carrier with an air line connecting it to a source of suction, a valve interposed in the line controlling the flow of air therethrough, a restricted flow of air being permitted through 120 the line when the valve is closed, a pneumatic device operably connected to the valve for opening the same, comprising a diaphragm, one side of which is subject to atmospheric pressure, the other side facing a 125 chamber which is provided with a port normally venting the chamber to the pressure in the line, and means responsive to the flow of air in the line caused by opening of said valve, adapted to close said port and cut off 130

- communication of said chamber with the line.
2. In the combination defined in claim 1, said chamber having an atmospheric vent controlling the operation of said means for opening the port to line pressure.
3. In the combination defined in claim 1, a timing valve venting said chamber to atmosphere for controlling the movement of the diaphragm to valve closing position.
- 10 4. In a pneumatic dispatch tube system including a transmission tube for a carrier with an air line connecting it to a source of suction, a valve interposed in the line controlling the flow of air therethrough, a restricted flow of air being permitted through the line when the valve is closed, a pneumatic device operably connected to the valve for opening the same, comprising a diaphragm, one side of which is subject to atmospheric pressure, the other side facing a chamber which is provided with a port normally venting the chamber to the pressure in the line, said valve being moved to open position by the reduction of pressure resulting when a carrier is inserted in the line, and means operable independently of and substantially simultaneously with the opening of said valve by the increased flow of air in the line for retaining said valve in open position for a limited period.
- 15 5. In a pneumatic dispatch tube system including a transmission tube for a carrier with an air line connecting it to a source of suction, a valve interposed in the line controlling the flow of air therethrough, a restricted flow of air being permitted through the line when the valve is closed, a pneumatic device operably connected to the valve for 75 opening the same, comprising a diaphragm, one side of which is subject to atmospheric pressure, the other side facing a chamber which is provided with a port normally venting the chamber to the pressure in the line, said valve being moved to open position by the reduction of pressure resulting when a carrier is inserted in the line, and means operable independently of and substantially simultaneously with the opening of said valve by the increased flow of air in the line for retaining said valve in open position for a limited period.
- 20 6. In a pneumatic dispatch tube system including a transmission tube for a carrier with an air line connecting it to a source of suction, a valve interposed in the line controlling the flow of air therethrough, a restricted flow of air being permitted through the line when the valve is closed, a pneumatic device operably connected to the valve for 80 opening the same, comprising a diaphragm, one side of which is subject to atmospheric pressure, the other side facing a chamber which is provided with a port normally venting the chamber to the pressure in the line, said valve being moved to open position by the reduction of pressure resulting when a carrier is inserted in the line, and means operable independently of and substantially simultaneously with the opening of said valve by the increased flow of air in the line for retaining said valve in open position for a limited period.
- 25 7. In the combination defined in claim 4, a spring normally tending to maintain said valve away from its port to vent the chamber to the line pressure.
- 30 8. In the combination defined in claim 4, a spring normally tending to maintain said valve away from its port to vent the chamber to the line pressure.
- 35 9. In a pneumatic dispatch tube system including a transmission tube for a carrier with an air line connecting it to a source of suction, a valve interposed in the line controlling the flow of air therethrough, a restricted flow of air being permitted through the line when the valve is closed, a pneumatic device operably connected to the valve for 85 opening the same, comprising a diaphragm, one side of which is subject to atmospheric pressure, the other side facing a chamber which is provided with a port normally venting the chamber to the pressure in the line, said valve being moved to open position by the reduction of pressure resulting when a carrier is inserted in the line, and means operable independently of and substantially simultaneously with the opening of said valve by the increased flow of air in the line for retaining said valve in open position for a limited period.
- 40 10. In a pneumatic dispatch tube system including a transmission tube for a carrier with an air line connecting it to a source of suction, a valve controlling the flow of air therethrough, means yieldingly holding said valve to its seat, and a suction motor normally connected with said air line and adapted for opening said valve; a second valve controlling communication of said motor with the line; a baffle disposed in the path of the air through said line and responsive to the flow of said air when the first mentioned valve is open, together with means connecting said baffle to the second valve for closing it when the first valve opens, and means for venting the suction motor to permit closure of said first valve by said yielding means.
- 45 11. In the combination defined in claim 6, said means including an apertured member, adapted to be adjusted relative to the aperture in the valve for varying the effective size of said aperture in the valve.
- 50 12. In the combination defined in claim 6, said means including an apertured member, adapted to be adjusted relative to the aperture in the valve for varying the effective size of said aperture in the valve.
- 55 13. In a pneumatic dispatch tube system including a transmission tube for a carrier with an air line connecting it to a source of suction, a valve interposed in the line controlling the flow of air therethrough, a restricted flow of air being permitted through the line when the valve is closed, a pneumatic device operably connected to the valve

SAMUEL OLSON.
